UNITED STATES PATENT OFFICE.

ANDREW TURNBULL, OF NEW BRITAIN, CONNECTICUT, ASSIGNOR OF ONE-HALF TO JAMES A. SWANSTON, OF SAME PLACE.

TOY CANNON.

SPECIFICATION forming part of Letters Patent No. 252,157, dated January 10, 1882.

Application filed June 24, 1881. (No model.)

To all whom it may concern:

Be it known that I, ANDREW TURNBULL, of New Britain, in the county of Hartford and State of Connecticut, have invented certain new and useful Improvements in Toy Cannons, of which the following is a specification.

My invention relates to improvements in toy cannons adapted for firing cartridges, in which the apparent cannon lies in the ordinary horizontal position, but is bored transversely, so that the barrel proper is vertical and discharges downward; and the objects of my improvement are to imitate a dangerous weapon, but which, in fact, fires downward, and therefore is perfectly harmless. I attain these objects by the simple construction represented in the accompanying drawing, which represents a vertical section through the middle of the cannon.

I prefer to mount the cannon A on wheels B in the ordinary manner; but it may be mounted upon any suitable frame, either with or without wheels, to bring it close to the ground or floor, and so sustain it in position that the discharge from it will always be fired downward, and never horizontal or upward. The cannon is of the ordinary form, and is bored in a short distance from its end to imitate the ordinary cannon; but, in fact, the longitudinal bore is too short to be of any service and has no provision for firing. The real bore or barrel proper, a, is formed at the breech of the cannon and extends transversely through it. This barrel is adapted to receive cartridges, which are inserted at the upper end. A hammer, C, of any ordinary construction, is provided, and so placed in relation to the barrel a as to strike upon the upper end of the cartridge to

explode it. I prefer to operate said hammer 40 to fire it by means of a string, b, so that the operator may stand back some little distance away from the cannon. I intend this cannon for firing blank cartridges; but the transverse barrel which fires downward will avoid all 45 danger, even if ball-cartridges are used.

I am aware that a prior patent shows a burglar-alarm consisting mainly of a square frame having a bore which extends transversely to the frame through the end which is 50 farthest from the hammer-pivot, and said patent also suggests that the device may be screwed upon the end of a pistol-handle. Said burglar-alarm, when used as a toy pistol, would be so far elevated above the user's feet and limbs 55 as to prove a very dangerous toy, much more so than the ordinary form of longitudinal bore, so that the transverse bore, instead of being an element of safety, as in my cannon, is converted into an element of danger by placing 60 it in a hand-pistol. The aforesaid burglar-alarm, either with or without a handle, is hereby disclaimed.

I claim as my invention—

A toy cannon consisting of the combination of an imitative cannon-barrel, A, having the barrel proper, a, extending transversely through its breech end, the hammer C, and a suitable frame upon which the barrel is mounted and sustained in position with the muzzle of 70 the barrel a pointing downward, so as to prevent it from being fired in any other direction, substantially as described, and for the purpose specified.

ANDREW TURNBULL.
